UNITED STATES PATENT OFFICE.

CHARLES MARION WOOLWORTH, OF OTTUMWA, IOWA.

DRILLING-MACHINE.

SPECIFICATION forming part of Letters Patent No. 396,018, dated January 8, 1889.

Application filed March 24, 1888. Serial No. 268,423. (No model.)

To all whom it may concern:

Be it known that I, CHARLES MARION WOOLWORTH, of Ottumwa, in the county of Wapello and State of Iowa, have invented certain 5 new and useful Improvements in Drilling-Machines; and I do hereby declare that the following is a full, clear, and exact description thereof, reference being had to the accompanying drawings, and to the letters of reference 10 marked thereon, which form part of this specification, in which—

Figure 1 is a front elevation of my improved drill. Fig. 2 is a side view of the same. Fig. 3 is a detail cross-sectional view of the 15 same.

This invention is an improvement in drilling-machines, and its objects are to improve the construction of hand-drills; and it consists in the novel construction and arrangement of certain parts hereinafter described, 20 illustrated in the drawings, and particularly specified in the claims hereto appended.

Referring by letter to the drawings, A designates the supporting-frame of the drill 25 composed of vertical side plates or bars, A' A', which have longitudinal re-enforce ribs or strengthening-flanges *a a* formed on their outer faces, as shown, which insure the rigidity of the bars. The bars are connected at their 30 upper ends by a sleeve, B, through which plays a vertical tube, B', which is adjustable through said sleeve, and is locked therein by a set-screw, B'', as shown. In tube B is placed a telescoping rod, b, which can be ad- 35 justably secured by a set-screw, b', in the upper end of tube B', as shown. The lower ends of bars A' A' are connected to a block, C, which has a central screw-threaded opening, in which plays a threaded rod, C', provided 40 with a setting-bar, c, as shown. The adjoining edges of bars A' at one side are formed with a series of corresponding notches, *a' a'*, for a purpose hereinafter shown.

D indicates the screw-threaded drill-shaft, 45 having diametrically-opposite longitudinal grooves, D'. d indicates a sectional nut, which is clamped upon shaft D, and through which the latter plays, and this nut is provided with opposite outstanding arms, d', which are placed 50 in opposite notches, *a'*, on the supporting-

frame and support the forward end of the drill-shaft and nut *d* thereon.

E is a rectangular metal frame, in which is journaled in suitable bearings the hollow shaft F of a bevel-gear, F', which shaft has beads 55 on its interior corresponding to the grooves in shaft D, and this shaft with its frame E is slipped upon rod D on the side of the frame opposite nut *d*, the beads engaging the grooves of the shaft, so that the latter will be rotated 60 with gear F', as is evident.

G designates a bevel-gear suitably journaled in one side of frame E and engaging gear F'. The shaft of gear G is extended beyond the frame and provided with an angular portion, *g*, and reduced screw-threaded portion *g'*, a slotted crank-arm, G', being engaged on portion *g* and secured thereon by a washer and nut, *g''*, on the threaded portion *g'*, as shown. This slotted crank-arm G', as 70 shown, allows the leverage of the crank to be varied.

From the inner corners of frame E project plates E' E', which are much wider than frame E and about as broad as the bars A' of the 75 frame are wide. These plates are planed on their outer faces so as to fit closely between the bars A' A' and brace the frame E against lateral movement, as is evident.

e e represent short lugs standing parallel 80 with plates E', but outside of the same, and adapted to embrace the outer edges of bars A' and prevent the latter from spreading if subjected to great lateral strain.

It will be observed that the frame E, in connection with the arms of nut *d*, supports the drill-shaft, and the frame is in turn supported upon the shaft. The gears turn the shaft, as is evident; but all the direct longitudinal strain on the shaft D is transferred through nut *d* 90 directly to the frame A. By reason of the notches *a'* the drill-shaft can be readily adjusted at different heights without changing the setting of the frame A, and the drill can be set at different angles for boring according 95 to the distance frame E is situated on the rod D from nut *d*.

To dismantle the drill, no unscrewing of bolts is required, the frame E being slipped off the shaft D, and the latter, with its nut *d*, 100

can be at once removed from the frame A, or the nut can be taken off the shaft and the frame E left thereon.

Having described my invention, I claim—

- 5 1. The combination of frame A, having bars A' A', provided with notches a' and ribs a, with the drill-shaft D, nut d, having arms d', and the frame E, carrying the driving-gearing for said shaft, provided with the brace-plates E' E', bearing against the inner faces of the bars A', substantially as and for the purpose described.
2. The combination of the supporting-frame A, having notched side bars, substantially as described, and the grooved drill-shaft D and nut d, having outstanding arms d', with the frame E, carrying the drill-shaft driving-gear and provided with plates E' E', bearing against the inner faces of bars A', and bracing the frame laterally, and lugs e e, all constructed and arranged substantially as and for the purpose described.
3. The combination of the frame A, composed of side bars, A' A', having ribs a and notches a', and the sleeve B, adjustable tube 25 B', and block C, with their adjustable rods and tubes, with the nut d, having arms d', the grooved shaft D, and the frame E, carrying the gears F' and G, with their shafts and cranks, and having the brace-plates E' E', engaging the inner faces of bars A', and the lugs e, engaging the outer edges of said bars, all constructed substantially as and for the purpose described.

In testimony that I claim the foregoing as 35 my own I affix my signature in presence of two witnesses.

CHARLES MARION WOOLWORTH.
